UNITED STATES PATENT OFFICE.

GORDON W. HALL, OF HAVANA, NEW YORK, ASSIGNOR TO HIMSELF AND
ALBERT O. WHITTEMORE, OF SAME PLACE.

PROPELLER FOR CANAL-BOATS.

SPECIFICATION forming part of Letters Patent No. 227,245, dated May 4, 1880.

Application filed February 17, 1880.

To all whom it may concern:

Be it known that I, GORDON W. HALL, of Havana, in the county of Schuyler and State of New York, have invented a new and useful Improvement in Propellers for Canal-Boats, of which the following is a specification.

The invention consists in a propeller having a hollow portion arranged to turn in the dead water under the stern of boat and connected 10 by a pipe with a condenser, as hereinafter described. These features will be more particularly described with reference to the accompanying drawings, forming part of this specification, wherein—

15 Figure 1 is a rear elevation of a boat fitted with my improved mechanism. Fig. 2 is a vertical longitudinal section of the stern portion of the boat.

Similar letters of reference indicate corresponding parts.

20 A is the boat. a is the propeller-shaft fitted in the stern, and B is the propeller-wheel upon the shaft a.

The wheel B consists of the central portion, 25 b, formed with the hub c and fitted with the blades d. The portion b is hollow, and is made in the shape of a frustum of a cone or a cylinder, with the end that is placed outward closed.

30 The stern of the boat A is finished off squarely, and the frustum b is of such a diameter that when conical its tapering sides are con-

tinuations of the lines of the boat, so that the portion b turns in the dead water, while the blades d project beyond the lines of the boat 35 into the solid water, where they have the greatest possible effect.

C represents the surface-condenser of the engine, the discharge-pipe e of which extends to the hollow portion b of the wheel near the 40 bottom.

The wheel B, by its revolution, will tend to create a vacuum in the part b, which will suck the water from the condenser through the pipe e, and a circulation will thus be kept up in the 45 condenser without the use of a special pump for the purpose, and the power to drive the pump will be saved.

This construction furnishes a propeller especially suitable for canal-boats of ordinary 50 construction, which will give the most effective application of the power used.

Having thus described my invention, I claim as new and desire to secure by Letters Patent—

55 The combination, on a canal-boat, of the hollow propeller B b and the condenser C of the engine, the two connected by a pipe, e, as and for the purpose specified.

GORDON W. HALL.
